UNITED STATES PATENT OFFICE

117,467

DESIGN FOR A HAND LUGGAGE CASE

William C. Chesnut, Racine, Wis., assignor to Hartmann Trunk Company, Racine, Wis., a corporation of Wisconsin

Application May 8, 1939, Serial No. 84,877

Term of patent 14 years

To all whom it may concern:

Be it known that I, William C. Chesnut, a citizen of the United States, residing at 912 Park Avenue, Racine, in the county of Racine and State of Wisconsin, have invented a new, original, and ornamental Design for Hand Luggage Cases, of which the following is a specification, reference being had to the accompanying drawing, forming part thereof.

In the drawing:

and end of a hand luggage case showing my new design; and

The design of the hand luggage case is characterized by a band of the specific configuration and arrangement shown.

I claim:

The ornamental design for a hand luggage case, as shown and described.

WILLIAM C. CHESNUT.
